[57] CLAIM

The ornamental design for a selector valve, substantially as shown and described.

DESCRIPTION

FIG. 1 is a left side elevation view of a selector valve showing my new design, the right side being essentially a mirror image of the left side shown;

FIG. 2 is a top plan view thereof;

FIG. 3 is a bottom plan view thereof;

FIG. 4 is a front elevational view thereof; and

FIG. 5 is a rear elevational view thereof.

*Fig. 1**Fig. 2**Fig. 3*
